UNITED STATES PATENT OFFICE.

HARRY L. NOLAN, OF MAPLEWOOD, MISSOURI.

PUMP FOR OIL WELLS.

Application filed January 17, 1921. Serial No. 437,796.

To all whom it may concern:

Be it known that I, HARRY L. NOLAN, a citizen of the United States, and residing at Maplewood, Missouri, have invented the 5 new and useful Improvement in Pumps for Oil Wells, of which the following is a specification.

This invention relates to pumps, and more particularly to deep well pumps employed 10 especially in oil wells.

A pump of the character referred to usually embodies a tubing or casing on the lower end of which is a working barrel, while the extreme end of the working barrel is provided with a perforated pipe or anchor. In 15 the lower end of the working barrel is mounted a lower or standing valve, while reciprocating in this barrel is an upper or working valve forming a plunger attached 20 to a sucker rod or wire cable so that upon reciprocation, the liquid will be pumped up through the barrel and the tubing.

Now it is often necessary to remove and replace the standing valve or element, and 25 in the present practice, this requires the complete removal of the working element together with the sucker rods or cable and the insertion of a rod bearing a gripping device adapted to grip the standing element in order 30 to permit withdrawal thereof from the casing. Now in replacement of the standing valve, this requires first the complete removal of the working element with its sucker rods or cable, second the insertion of 35 a gripping element on the end of a rod or a cable, third the withdrawal of the gripping element with the standing valve, fourth the insertion of a new standing valve, and fifth the replacement of the working valve with 40 its sucker rods or cable. These operations require a great deal of time which is a very important and valuable factor, especially in the pumping of oil wells.

One of the objects of this invention, therefore, 45 is to provide a pump whereby the removal and replacement of a standing valve may be accomplished with a minimum of labor and expense.

Another object is to provide a pump 50 whereby the standing valve or element may be withdrawn by the working element.

Another object is to provide a means to prevent injury to the standing and working valves during normal operation.

55 Another object is to provide means whereby the standing element may be withdrawn

by the working element and which shall offer a minimum of interference to the flow of liquid during the pumping operation.

Further objects will appear from the detail description taken in connection with the accompanying drawing, in which:

Figure 1 is a longitudinal vertical section through the working barrel and anchor of a deep well pump embodying this invention;

Figure 2 is an enlarged detail view, partially in section showing the means for attaching the standing element to the working element; and

Figure 3 is a view similar to Figure 2, but showing these elements in attached position.

Referring to the accompanying drawing, 1 designates the barrel of the pump which is provided at its lower end with a perforated 75 tube or anchor 2. The standing element 3 is inserted in the barrel and is provided with a collar 4 usually of leather or similar material, arranged to form a tight fit in the barrel. This standing element is inserted 80 usually by dropping it in from the top of the well and by virtue of the momentum acquired during its fall, it lodges tightly in the barrel at the proper point, which is usually slightly reduced in diameter at that 85 point and for that purpose. The standing element is provided with a ball valve 5 enclosed in a cage 6 of well known form. The working element 7 is also provided with a ball valve 8 working in a cage 9 and is 90 further provided with a series of washers 10 of leather or similar material closely fitting the inner body of the barrel. The ball valve 8 closes the upper end of a vertical central duct through the lower body of the 95 working element through which the liquid is worked upward by the action of the pump upon reciprocation of the working element.

The parts so far described are all of the usual construction well known in the art and 100 will, therefore, require no further description. In the present device a tapered tap or thread-cutting element 11 having a threaded shank 12 is mounted on the upper portion of the cage 6 of the standing element so 105 as to extend vertically upward therefrom. Mounted on the shank 12 and having screw-threaded engagement therewith is a hollow sleeve 13 having a bore 14 adapted to receive the tap 11. The sleeve 13 is screwed 110 upward on the shank 12 against a shoulder 15 on said shank adapted to limit its up-

ward movement. The sleeve 13 is held in its upper position by means of a coil spring 16 surrounding the shank 12 and bearing at one end against the cage 6 and at the 5 other end against the end of a hollow chamber 17 in the lower end of the sleeve 13. The shank 12 may be provided with a hole 18 for the insertion of a pin to be used in screwing the shank into the cage 6.

10 The upper face of the sleeve 13 is provided with a clutch 19 adapted to engage a corresponding clutch face 20 on the lower end of a cage 21 attached to the lower end of the working element 7. The cage 21 may 15 be provided with a central perforation 22 adapted to engage the tap 11 and which may be interiorly threaded to correspond with the threads of said tap.

19 In assembling the device, the sleeve 13 is first screwed onto the shank 12 from the bottom end up to the shoulder 15. The spring 16 is then slipped over the shank and the latter screwed into the cage 6, being 20 securely tightened by means of a pin in the 25 hole 18.

When the standing element 3 with the parts thus assembled is dropped into the well tube, the sleeve 13 will occupy its position at the upper end of the shank 12 and covering the tap 11 so as to protect the same from injury. The sleeve will be held in this 30 position throughout the normal working of the pump by the spring 16. If as sometimes happens the standing element 3 should not 35 lodge in the correct position in the barrel, it can be forced to that position by the usual method of pounding it down with the working element and during which operation the tap 11 will be effectively protected by the 40 sleeve 13 which forms a shock receiving element adapted to take the blows of the working element during such an operation. It will also be seen that the flow of liquid will suffer a minimum interference from this 45 device, especially the passage of the liquid through the working element 7 which is provided both with said openings 23 of the cage 21 and with the central perforation. The tap 11 is mounted on the standing 50 element rather than on the working element for the reason that in the latter case, it will interfere more seriously with the flow of liquid to and through the rapidly reciprocating element 7 and it would also be very 55 liable to work loose on account of such rapid

reciprocation and the vibration consequent to its weight and inertia.

When it becomes necessary to remove the standing element from the well, it is only necessary to lower the working element and 60 then rotate the sucker rods through a dozen revolutions or so whereupon the clutch face 20 will engage the clutch face 19 and subsequent rotation will not only work the sleeve 13 downward on the shank 12 but will 65 also engage the tap 11 in the perforation 22 so as to securely screw it into the cage 21 to form a rigid connection between the standing and working elements; the tap cutting its way into the working element. 70 As the sleeve 13 is screwed downward on the shank 12, the spring 16 will be compressed. When the sleeve reaches the limit of its downward movement, the spring will 75 be confined within the chamber 17 and will consequently be protected from injury so that the device can again be restored to its original condition by simply screwing the sleeve 13 back to the top of the shank 12.

It is obvious that various changes may be 80 made in the details of construction without departing from the spirit of this invention; it is, therefore, to be understood that this invention is not to be limited to the specific details shown and described.

Having thus described the invention, what is claimed is:

1. In a well pump having a working element provided with a perforation, a standing element, and a tap on said standing element adapted for cooperation with said perforation, substantially as and for the purpose set forth.
2. In a well pump having a working element provided with a perforation, a standing element, a tap on said standing element adapted for cooperation with said perforation, and a guard for said tap, substantially as and for the purpose set forth.
3. In a well pump having a working element provided with a perforation, a standing element, a tap on said standing element adapted for cooperation with said perforation, and a guard for said tap mounted on said standing element and cooperating with said working element, substantially as and for the purpose set forth.

In testimony whereof I affix my signature this 2nd day of December, 1920.

HARRY L. NOLAN.
